COMPACT

Solomon Young, Stamford, Conn., assignor to The Zell Products Corporation, Norwalk, Conn., a corporation of Connecticut

Application February 11, 1955, Serial No. 34,488

Term of patent 14 years

(Cl. D86—10)(7)

Fig. 1 is a front elevational view of a compact showing my new design;

Fig. 2 is a similar view, with the lid open;

Fig. 3 is a side elevational view thereof.

I claim:

The ornamental design for a compact, substantially as shown.
